UNITED STATES PATENT OFFICE.

JOHN R. CAMPBELL, OF DES MOINES, IOWA.

DESIGN FOR A GAME-BOARD.

No. 39,517.

Specification for Design.

Patented Sept. 8, 1908

Application filed June 15, 1908. Serial No. 438,686. Term of patent 3½ years.

To all whom it may concern:

Be it known that I, JOHN R. CAMPBELL, a citizen of the United States, residing at Des Moines, in the county of Polk and State of Iowa, have invented a new, original, and ornamental Design for Game-Boards, of which the following is a specification, reference being had to the accompanying drawing, forming part thereof.

The figure is a plan view of a game board, showing my new design.

I claim:
The ornamental design for a game board as shown.

Des Moines, Iowa, May 25, 1908.

JOHN R. CAMPBELL.
